BRIDGE SCORING DEVICE

Anne G. Hatch, Bronxville, N. Y.

Application July 2, 1935, Serial No. 29,444

11 Claims. (Cl. 235—87)

The invention relates in general to a bridge score indicating device for use by a scorer for indicating to the players at the table as well as to himself the current suit and number of tricks bid, as well as the status of the bid, whether vulnerable, doubled and the like, and also for indicating to himself the proper numerical value authorized to be placed above and below the line on the score pad when the indicator is set to the number of undertricks or overtricks made at the conclusion of the current game. It will show the board that the score is being calculated on the proper basis.

The primary object of the invention is to provide a simplified, easily manipulated and accurate indicating form of device of the type outlined and which may be easily and quickly set to show the bid and incidental status of the winning side on the side facing the board and which will automatically indicate on the opposite side facing the scorer when set by him to register the number of over or under tricks, the proper numerical value to be marked above and below the line on the final scoring pad.

25 The invention has for another object the providing of notice impelling designations to signal to the scorer or operator that certain numbers have a relatively negative significance that is to be credited to the losers of the original bidding.

30 Various other objects and advantages of the invention will be in part obvious from an inspection of the accompanying drawings and in part will be more fully set forth in the following particular description of one form of indicating device embodying the invention, and the invention also consists in certain new and novel features of construction and combination of parts herein-after set forth and claimed.

In the accompanying drawings:

40 Fig. 1 is a view in front elevation, that is, on the side facing the scorer, of a preferred embodiment of the invention; and

45 Fig. 2 is a corresponding view in rear elevation of the opposite side facing the board, players or observers;

Fig. 3 is a plan view looking down upon the showing in the preceding figures;

Fig. 4 is an enlarged vertical sectional view taken on the medial plane axially of the rotors indicated by the line 4—4 of Fig. 3 looking in the direction of the arrows;

Fig. 5 is a transverse vertical sectional view taken on the plane indicated by the line 5—5 of Fig. 4 looking in the direction indicated by the 55 arrows;

Fig. 6 is a fragmentary view of the upper right hand portion of the casing shown in Fig. 4 and with the adjacent rotor removed;

Figs. 7 and 8 are developed views in plan of the cylindrical surfaces respectively of the left and 5 right hand drums shown in Fig. 4; and

Fig. 9 is a developed plan view of the curved shield shown in section in Figs. 4 and 5.

Referring particularly to the showing of the containing casing 10 in the several figures, it 10 will be noted from Fig. 5 that it is of somewhat semi-cylindrical form with the opposing straight vertical sides 11 and 12 between the wide lower edges of which is fitted a block form base 13 and which casing includes oppositely disposed ends 15 14 and 15 provided respectively with circular end openings 16 and 17. Each of the sides 14 and 15 is provided with an inwardly extending annular flange 18 providing at their inner peripheries external bearings for rotors hereinafter described, 20 and providing on their outer peripheries a bearing for mounting opposite edges of a shield hereinafter described.

The side of the casing facing the scorer, as shown in Fig. 1, is provided with three windows 25 disposed in line. The right hand window is marked above the same "Score below line"; the middle window 21 is marked thereabove "Score above line" and the third, relatively narrow window 22, sometimes hereinafter referred to as the 30 "Trick Number" window, is marked on opposite sides "Under Tricks" and "Over Tricks".

On the opposite side of the casing, that is, the side facing the board as indicated in Fig. 2, there is provided two aligned windows, the one at the 35 right 23 corresponding to the window 22 and offset from the adjacent side 16 a distance greater than the distance the window 22 is spaced, by an amount equal to one of the columns hereinafter described. The other window 24 in line with window 23, designated as the "Bid" window has its right hand part, if transversely projected, overlapping part of the window 21.

The front side of the casing as shown in Fig. 1 is provided with a vertically disposed slot 25 and 45 in which is a shield actuating thumb piece 26. An edge of the slot 25 is preferably provided with a plurality, in the instant case shown to be six, equidistantly spaced stops, recesses or grooves 27 for receiving a spring pressed detent 28 carried 50 on the adjacent side of the finger piece 26.

Referring to the interior structure within the casing, there is shown in Fig. 4 two rotors 29 and 30 mounted for rotary movement about a common axis indicated by the line a—b and each 55

provided with an outwardly and axially projecting knob designated respectively 31, 32, and located respectively in the openings 16 and 17. In each case the knob is knurled as indicated at 5 33 to facilitate manual rotation of the associated rotor. In the illustrated embodiment the rotors are mounted for independent rotary movement and mounted in the external bearing provided by the flanges 18 and are maintained in their 10 pressed apart relation and resiliently forced into engagement with the sides 14 and 15 by means of a shaft 34 projecting integrally from rotor 29 and having its outer end intruded into a bore 35 formed in the hub of rotor 30. An anti-friction 15 ball roller 36 with spring 37 bearing on the ball is located in the bore 35 and tends to press the rotors apart and into engagement with the sides 14 and 15. In order to set the rotors into their 20 rotatably adjusted positions against accidental displacement from any position in which they may be set by the operator, it is herein suggested that the inner wall of the ends 15 and 16 and the edge portion of the rotors 29 engaging the same be knurled, corrugated or roughened, as indicated at 38, preferably to correspond to definite 25 positions of the rotors.

The rotor 29 is provided with a cylindrical drum 40 which projects therefrom towards the other rotor 30 and the rotor 30 is provided with 30 a drum 41, the left hand edge portion of which overlaps the right hand edge portion of the drum 40 as shown in Fig. 4. The cylindrical surfaces of the two drums are provided with columns of bridge scoring indices, status data, bid indicating data and blocks of opaque and transparent 35 areas in the overlapping portion of the drum 41, as will be hereinafter described with specific reference to Figs. 7 and 8.

Positioned between the drum and the two lines 40 of sight windows in the casing is a shield 42 of a little less than complete cylindrical form as shown in Fig. 5 and mounted for limited rocking movement about the axis $a-b$.

Referring to the developed showing of this 45 shield in Fig. 9, it will be noted that it is provided with a plurality of openings for selectively exposing to view certain indicia and data and simultaneously concealing from view certain other indicia and data on the portion of the drums framed in the several sight openings in the different rotative positions of the drums. At one 50 of the limiting positions of the drum, that is on the end facing the windows 23 and 24 and as shown at the upper portion of Fig. 9, there are found two long parallel openings, the left narrow slit 43 adapted to expose the trick numbers hereinafter described through the window 23 and the relatively wider slit 44 disposed to disclose bid data through the left hand part of window 24 as 55 shown in Fig. 2. It is noted that adjacent the window 44 are writings disposed in six lines; sometimes referred to hereinafter as "Status Designations", and in the instant case reading from the adjacent edge "ReD Vul", "Dbl Vul", and "Vul", on one half of the slot and "Not Vul", 60 "Dbl NV", and "ReD NV" on the other half. These several status indications are designed to be exposed selectively through the right hand side of window 24 depending upon which of the 65 fixed selective positions the shield may be shifted by the manipulation back and forth of the thumb piece 26.

Referring to the lower portion of the shield as 70 shown in Fig. 9, it is provided adjacent its left edge and out of line with slot 43 with a corre-

spondingly long slot 46 adapted to register with the window 22. At the lower right hand side of this figure (9) is a T shaped slot 47 with its head portion extending parallel to the slot 44 and similarly designated with the same status identifying 5 designations 48 having such a relation with the designations at the slot 44 as to be up-side-down relative thereto and symmetrically disposed. In other words "ReD Vul" is at the upper end of slot 47 but is at the lower end of slot 44 as viewed 10 in Fig. 9. Adjacent slot 47 the shield is provided with other block shaped openings 50 adapted to register with the right hand side of window 20 and the openings are so arranged that each line of opening is differently arranged from the openings in every other line and arranged to co-operate selectively with the proper numerals in 15 the three right hand columns of the showing in Fig. 8.

Adjacent the center of the lower portion of 20 shield 42 is a stepped form of opening 51 adapted to register with the right hand side of the window 21 and with a plurality of openings in 25 relatively staggered relation designated collectively as 52 and in each case provided with two zero characters 53 for cooperating with the bonus score values on the chart shown in Fig. 7 as hereinafter described.

Referring to the chart on cylinder 40 and 30 specifically to the developed showing thereof in Fig. 7, the surface is divided into a plurality of circumferentially extending parallel columns with printing therein disposed in succeeding lines parallel to the axis of rotation of the rotors. There is provided a longitudinally extending 35 blank space 54 hereinafter sometimes referred to as the neutral position on which there is shown a pointing character 55. The two left hand columns extending the entire length are referred to hereinafter as trick number columns with the left hand column 56 registering with window 22 and provided with two sets of numbers positioned on opposite sides of the neutral position 54 and progressing therefrom, one set 40 extending upwardly and designating from 1 to 13, and the other set progressing downwardly and numbered from 1 to 6. The second column is likewise provided with two sets of numbers, one set from 1 to 6 and the other set from 1 to 55 13, with the space 58¹ in this second column blank in its position parallel to the set of numbers from 1 to 6 in the column 56. The figures in the column 57 are reversed in position, that is, are in an up-side-down position relative to the 55 figures in column 56. The up-side-down figures of column 57 when registering in window 23 will, of course, be in the upright position shown in Fig. 2. To the right of column 57 and above neutral positions 54 are arranged six columns 58 60 containing penalty score figures having a pre-fixed relative relation or value designated by bridge authorities to represent values of the number of tricks designated in the left hand column 56. It is understood that the numerals 65 appearing in the five columns to the left thereof are used only in conjunction with the double zeros 53 appearing in the shield (Fig. 9) adjacent the openings 52. The two right hand columns 59 and 68 above the neutral positions 54 70 opposite the 1 to 13 set of figures are provided with arrows pointing to the left. It is herein suggested that the penalty figures of the scale above the neutral position 54 be formed of a red or some other color vividly contrasting with the 75

other numbers present on Fig. 7. To the right of column 57 and below the neutral position 54 are arranged eight columns in the following manner. As viewed in the figure, three sets of numbers of two columns each showing bonus score figures having a prefixed relative relation, a value designated by bridge authorities to represent values of the number of tricks designated in the left hand column 56. It is understood that the numerals shown in the two left hand sets of columns are used only in conjunction with the double zeros 53 appearing on the shield (Fig. 9) adjacent the openings 52. These sets of numerals are separated by columns showing arrows pointing to the right. It is appreciated that by rotating the left knob 33 any left hand column numbered line is brought into registration with windows 22 and 21 and that the identical figure indicating the tricks designated in the corresponding sets in column 57 are simultaneously brought into registry with the windows 23. Referring to the drum 41 and to the scale shown in Fig. 8 which may be referred to as the bid scale, it is similarly provided with printing matter to form three right hand columns 62 of trick values apportioned by the bridge authorities to the bid designations in the next adjacent column 63. In column 63 the different bids beginning with the lowest bid of One Club are arranged in order of progressively increasing values to Seven No Trump. In the next adjacent column 64 to the left of 63 is provided similar bid designations arranged in an up-side-down relation to the showing of the characters in column 63 and likewise progressing, considered circumferentially of the drum, and from one point therein with characters of increasing value. The characters in the columns 63 and 64 are arranged relative to their coacting sight windows 20 and 24 so that identical characters are simultaneously displayed through the windows on the opposite sides of the casing and in their correct upright positions as shown in Figs. 1 and 2.

The left edge portion of the right hand drum shown in Fig. 8 and which is the overlapping portion of the cylinder 41 as shown in Fig. 4 is formed of alternate blocks or sections of transparent areas 65 and opaque areas 66 arranged so that as any selected line is moved into registry with the window 21 either a transparent or an opaque block 65 will overlap and thus either display or conceal whichever character in column 59 may happen for the time being to be registering with window 21. Likewise, in every rotated position of Fig. 8, either an opaque or a transparent portion of the column 66 will be exposing or concealing either the arrow or one of the figures for the time being registering with the window 21.

It is thus seen that the particular group of characters exposed through the different windows is dependent upon three controllable factors; first, upon the rotative position of the rotor 29; second, upon the rotative position of the rotor 30; and third, upon the position into which the shield is rocked at any particular setting of the device.

For instance, in the exemplary showing in the several figures, the final bid was Three Hearts, the bidding side was not vulnerable and if the bidding side should win, they are entitled to a score of 90 below the line as indicated in window 20. In the illustrated case, they did not make the contract but were two tricks short and the

indicator thus shows by the red character 100 in window 21 that the opponents were entitled to a score of 100 above the line. These readings were obtained first by the manipulation of the thumb piece 26 until the "Not Vul" indication appeared in windows 20 and 24. Then by the rotation of the right hand knob 32, the operator rotated the scale of Fig. 8 until the designation of Three Hearts appeared in both of the windows 20 and 24. This also automatically and by virtue of the stem portion of the T shaped slot 47 brought the "90" into registry with the window 20 and the device remained as thus set "Three Hearts", "90", "Not Vul", until the conclusion of the game.

At the conclusion of the game, and in the instant case, the winners of the bid having failed by two tricks to make their contract, the scorer rotates the left hand drum counterclockwise as viewed looking into the left end of the casing in Fig. 1, by the manipulation of the handle 33 until the red "2" in the upper part of the chart of Fig. 7 registers in both of the windows 22 and 23 and at the same time by the combination of the form of the opening 51, the penalty score of 100 for the opponents appears adjacent the middle of window 21.

It will thus be seen that by means of the device disclosed it is possible simply by rotating the right hand knob to indicate the successive bids of the different sides or playing couples and with each bid there is simultaneously presented at least to the scorer "the below the line" value of that particular bid, and eventually when the bidding is finished the final bid designation with the score at that bid and the status of the bid, vulnerable, etc., is permitted to remain until the game is concluded and the score is entered on the final score pads. As the bidding progresses the scorer by manipulating the thumb piece 28 indicates other data such as whether the bidding side is vulnerable or whether there is a double or redouble at the different steps of the bidding and at the final bid.

The final set position of the shield, of course, controls the score value to which the winning side is entitled in the different vulnerable, doubled, and redoubled situations and which are indicated respectively in the columns 62.

By the simple manipulation of the left hand rotor to the red position the characters in the case of undertricks or to the black position of the characters in the case of overtricks, only the proper score value is automatically and promptly presented to the scorer, thus avoiding any necessity of the checking of the score with approved reference tables as is usual in card tournament events.

While there have been shown, described, and pointed out in the annexed claims, certain novel features of the invention, it will be understood that various omissions, substitutions and changes in the form and details of the bridge score indicating device illustrated and in its operation may be made by those skilled in the art without departing from the spirit of the invention.

I claim:

1. A bridge score indicating device including a mechanism containing casing provided with sides facing in opposite directions, one side provided with windows arranged in line and designated a "trick number" window, a "score above line" window and a "score below line" window, and the other side provided with two windows arranged in line and designated a "trick" window 75

and a "bid" window with an end of the bid window when transversely projected lapping the "score above line" window on the other side and the trick number windows being both adjacent one end of the casing, two cylinders mounted for independent rotary movement in the casing, one for each score window, and an end of one cylinder provided with transparent and opaque blocks lapping the adjacent end of the other cylinder and registering with the laterally projecting lapping portions of the "bid" and "score above line" windows, each cylinder provided on its cylinder surface with a plurality of columns of bridge indicia arranged in lines and each line adapted to register with their respective "score above line" and "score below line" windows, two of the columns on the cylinder adjacent the trick windows being each provided with consecutive numbers one to thirteen arranged in relatively reverse order and adapted to be rotated with the associated cylinder to expose selectively the same number in the two trick number windows, and an opaque shield mounted for rocking movement about said axis, disposed between the cylinders and the part of the casing provided with the windows and provided with variously positioned openings for selectively exposing and concealing certain of the indicia on the cylinders as the shield is shifted relative to the casing windows.

2. In a device of the class described, the combination of a casing provided with a "score above the line" window and a "score below the line" window, a pair of cylinders one for each window mounted for rotary movement about a common axis and each provided with circumferentially arranged columns of score indicia arranged in equi-width lines extending parallel to said axis and each line adapted to be rotated into position to register with its associated window, and an opaque shield provided with a plurality of lines of sight openings, the sight opening of each line being differently arranged from the sight opening of every other line and said shield disposed in adjusted position over the portions of both of the cylinders registering with the windows selectively to expose certain of the cylinder indicia while concealing other of the cylinder indicia in the line of each cylinder for the time being registering with its respective window, said shield being shiftable in both directions from a mean position in the direction of the length of the columns and said shield having similar indicia thereon equidistantly spaced on opposite sides of a line of reference, the data on one side having a positive value, such as "vul." and the corresponding data on the other side having a relatively negative value such as "not vul."

3. A bridge score indicating device comprising a casing, two cylinders mounted therein for independent rotary movement about a common axis and having an edge portion of one overlapping an edge portion of the other, said cylinders provided on their cylinder surfaces with a plurality of circumferentially extending columns of bridge scoring and bridge bidding indicia arranged in equi-width lines parallel to the axis, the overlapping portion forming two columns of blank sections, one of the two column sections of each overlapping line being transparent to expose an indicia beneath the same on the overlapped portion and the other column section being opaque to conceal the indicia beneath on the overlapped portion of the other cylinder and said casing pro-

vided with two long narrow windows having a width equal to that of the lines, one for each cylinder, extending parallel to said common axis and each adapted to frame a line or part of a line of indicia on its associated cylinder and one of the windows disposed to expose the overlapping portion, and an opaque shield mounted for a limited rocking motion about said axis and provided with lines of apertures, variously located relative to exposed columns of indicia on the cylinders and acting selectively as it is shifted relative to the windows to expose certain indicia through the windows and the opaque portion of the shield acting to conceal other indicia which would otherwise be exposed through the windows. 15

4. In a device of the class described, the combination of a casing provided with two windows arranged on opposite sides thereof and facing in opposite directions, a cylinder provided on its cylinder surface with two parallel columns of 20 characters representing card bids, with the characters in one column upside down relative to the characters in the other column, the value of the bids progressively increasing in one column as read down the column and the value of the bids 25 progressively decreasing as read down the other column and said windows located relative to the cylinder so that when the cylinder is rotated into any position the same bid character registers in both windows so as to be visible from opposite 30 sides of the casing, and said cylinder provided with other parallel columns provided with figures corresponding to values assigned to the different bids indicated in one of said bid columns, under different controlling conditions and an adjustable shield overlapping the other parallel columns and having a plurality of positions into which it may be shifted and said shield provided with both opaque and non-obstructing portions selectively covering and exposing certain of said figures in 40 the last mentioned parallel columns depending on the position into which the shield is shifted.

5. A bridge score indicating device comprising a casing, two cylinders mounted therein for independent rotary movement about a common axis 45 and having an edge portion of one overlapping an edge portion of the other, said cylinders provided on their cylinder surfaces with a plurality of circumferentially extending columns of bridge scoring and bridge bidding indicia arranged in 50 equi-width lines parallel to the axis, the overlapping portion forming two columns of blank sections, one of the two column sections of each overlapping line exposing indicium beneath the same on the overlapped portion and the other column 55 section being opaque to conceal the indicium beneath on the overlapped portion of the other cylinder and said casing provided with two long narrow windows having a width equal to that of the lines, one for each cylinder, extending parallel to said common axis and each adapted to contain a line or part of a line of indicia on its associated cylinder and one of the windows disposed to expose the overlapping portion.

6. In a device of the class described, the combination of a casing provided with a "score above the line" window and a "score below the line" window, a pair of cylinders one for each window mounted for rotary movement about a common axis and each provided with circumferentially 65 arranged columns of score indicia arranged in equi-width lines extending parallel to said axis and each line adapted to be rotated into position to register with its associated window, and an opaque shield provided with a plurality of lines 70

5 of sight openings, the sight opening of each line being differently arranged from the sight opening of every other line and said shield disposed in selectively adjusted position over the portions of both of the cylinders registering with the windows to expose certain of the cylinder indicia while concealing other of the cylinder indicia in the line of each cylinder which for the time being is registering with its respective window.

10 7. In a bridge score indicating device, the combination of two cylinders mounted for rotary movement about a common axis and each provided on its cylinder surface with a plurality of columns of indicia arranged in lines, a casing provided with a pair of sight windows, each adapted to frame certain of the lines of indicia on one of the cylinders and a shield positioned between the cylinders and the windows and having a plurality of set positions, the shield provided with a plurality of differently arranged openings, one registering with one of the windows in one set position of the shield and acting when in such set position to expose certain of the indicia on the cylinder and to conceal other such indicia 25 in the lines which would otherwise be exposed through the window.

8. In a bridge score indicating device, the combination of a casing provided with a pair of trick number windows facing in opposite directions and provided on one side with a score window, a cylinder mounted in the casing for rotation about its axis and provided on its cylinder surface with a plurality of columns of bridge score figures arranged in lines to register with the score window and also provided with two columns of numbers, one of the columns located to pass one of the trick number windows and the other column located to pass the other trick number window, the numbers in one column being arranged in two sets, one set increasing progressively from one to six and located on one side of a neutral position and from one to thirteen on the other side, and the figures in the other trick column being upside down relative to the figures 40 in the first trick column, said other trick column being blank in the space parallel to the set of one to six numbers in the first column, the numbers in the other column being also arranged in two sets, one set with the figures progressing from 45 one to six and the other set progressing from

one to thirteen and the fingers in the two number columns coacting with the location of the trick number windows to cause the identical number in the corresponding set to register simultaneously with both number windows.

5

9. In a device of the class described, the combination of two cylinders mounted for rotary movement about a common axis with an edge portion of one cylinder overlapping an edge portion of the other cylinder and said overlapping portion having opaque and transparent sections for selectively concealing and exposing the overlapped portion of the other cylinder, each cylinder provided on its cylindrical surface with a plurality of columns of indicia arranged in lines 15 parallel to said axis, a casing provided with at least three line framing windows, at least one for each cylinder, and one of the windows located to expose to view the overlapping portions of the two cylinders.

20

10. In a bridge score indicating device, the combination of a plurality of windows, a plurality of manually controlled cylinders independently movable relative to each other to register at will with the several windows bridge scoring data on 25 their cylindrical surfaces, and shielding means provided with openings for exposing selectively different parts of the data for the time being registering with one of the windows and provided with opaque portions for concealing selectively 30 different parts of the data which for the time being is registering with another of said windows.

35

11. In a bridge score indicating device including means having a pair of sight windows facing in opposite directions, a strip on one side of the windows provided with three columns of bridge score data arranged in lines in prefixed relative order and adapted to be shifted at will to cause lines of the same selected data to register with the windows, the data of two columns being arranged on the strip in cooperative relation with the pair of windows to cause the same data to be exposed simultaneously through each window and a third window with which the data of the third column registers, said third window being 45 arranged relative to the said pairs of sight windows to expose to view data associated in bridge score values with the data simultaneously exposed through the pair of windows.
